Primary Examiner — W. A. Teddy Falloway(74) *Attorney, Agent, or Firm* — Chun-Ming Shih(57) **CLAIM**

The ornamental design for a smart mirror, as shown and described.

DESCRIPTION

FIG. 1 is a perspective view of a smart mirror showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is a perspective view showing the smart mirror in use. The broken lines in the drawings illustrate portions of the smart mirror that form no part of the claimed design.
